UNITED STATES PATENT OFFICE.

FRANK KAPINOS AND GEORGE CHIZEK, OF CANBY, MINNESOTA.

GRAIN-SHOCK LOADER.

1,378,240.

Specification of Letters Patent.

Patented May 17, 1921.

Application filed July 25, 1917, Serial No. 182,749. Renewed October 15, 1920. Serial No. 417,279.

To all whom it may concern:

Be it known that we, FRANK KAPINOS and GEORGE CHIZEK, citizens of the United States, residing at Canby, in the county of Yellow Medicine, State of Minnesota, have invented certain new and useful Improvements in Grain-Shock Loaders; and we do hereby declare the following to be a full, clear, and exact description of the invention, 10 such as will enable others skilled in the art to which it appertains to make and use the same.

This invention relates to loading machines, and has particular reference to loading 15 shocks of grain upon carriers.

The object of this invention is to provide a machine for effectively and practicably removing shocks of grain from the field and loading them upon the rack or other vehicle.

20 A further object of the invention consists in the provision of a suitable means for driving the conveyer belts, which carry the bundles from the ground to a suitable elevation for loading, and also for operating 25 the means for transferring bundles or shocks from the elevating conveyers to a rack.

As a further object, the invention contemplates the construction of suitable coöperating upper and lower conveyer belts between 30 which the shocks are gathered for elevation.

With the above objects in view, and such others relating to the details of construction as may hereinafter appear, our invention will now be fully set forth and described, 35 reference being had to the accompanying drawings.

In the drawings:—

Figure 1 is a side elevation of the machine,

40 Fig. 2 is a plan view,

Fig. 3 is a detail perspective view of part of the driving means,

Fig. 4 is a detail elevation of another part of the driving means,

45 Fig. 5 is a detail sectional view,

Fig. 6 is a detail view of the chain tightener,

Fig. 7 is a detail of the lower conveyer belt, and

50 Fig. 8 is an enlarged detail view of the upper conveyer belt.

Referring more particularly to the drawings, the present invention includes a carrying frame which consists of horizontal 55 beams 6, having uprights 7 at their rearward ends and having upwardly and for-

wardly inclined standards 3 at their forward ends, these standards extending above and below the beams 6.

Upper and lower rectangular frames 1 60 and 2 are supported by the uprights 7 and the standards 3 in parallel relation to each other, these frames 1 and 2 being inclined upwardly and rearwardly, and the lower frame 2 is supported at its forward end by 65 ground wheels 8 pivotally mounted so that the machine may be steered through the medium of suitable steering gear and a steering column 10 which may be reached from a driver's seat 11. Traction wheels 9 70 are carried by an axle 52 journaled across the beams 6.

Mounted upon the forward end of the frame 2 is a rake 12 which has a series of 75 forwardly projecting teeth adapted to pass over the ground and gather the bundles therefrom. The tooth bar 13 of the rake carries an upwardly extending standard 14 whose upper end is connected to a chain 15.

The chain 15 passes over a pulley 16 carried by the upper end of the standard 3, and passes thence to a hand lever 17 which is mounted upon the beam 6 adjacent the driver's seat, and is held in its position of adjustment by the engagement of a pawl of 85 usual form with a segment 18.

The upper frame 1 supports an upper endless conveyer consisting of a pair of chains 20 which operate upon the sprockets 19 at opposite sides of the frame, and transverse 90 flat bars 21 which join the chains 20 at spaced intervals throughout their lengths. Each of the bars 21 is provided with a suitable plurality of spikes or studs 22. The chains are tensioned by means of a pair of 95 sprocket wheels 23 which are mounted in brackets 24 slidably carried by the forward standards 3. The brackets 24 are held in their positions of adjustment by means of bolts 25 which pass through the brackets 24 100 and also through selected openings in the standards 3.

The lower frame 2 also supports an endless conveyer, upon the upper and lower sprocket wheels 26. The side chains 27, of 105 this conveyer, are connected by transverse angle bars 28 whose vertical sides constitute the abutments which coöperate with the studs 22 of the upper conveyer to carry bundles upwardly between the frames. The 110 upper run of the lower conveyer operates upon a sheet metal bottom plate 29 which

extends across the area of the frame 2, and is suitably held between and by the side rails thereof, the sheet metal bottom 29 being designed to support the bundles between 5 the abutments of the lower conveyer.

The upper and lower conveyers are driven from a gear 30 which is carried by one of the traction wheels 9, and meshes with a gear 31 mounted upon a stub shaft 32 which is 10 carried by the frame-work. Also mounted on the stub shaft 32 is a sprocket wheel 33 over which a chain 34 is operated, said chain also running over a sprocket 35 mounted on the stub shaft 36. From these sprockets 35, 15 a chain 37 operates to drive a gear 38 which in turn meshes with a gear 39 mounted upon the shaft of the upper sprocket wheels 19. Extending transversely across the back of the frame-work of the machine, is a trough 20 40 into which the grain is delivered from the upper ends of the elevating conveyers. The trough is longitudinally divided along its median line, and the sections are spaced for sprockets 41 and 41' which are mounted on 25 shafts 44 and 44' connecting the sections and support a conveyer 42, the upper run of the conveyer 42 coinciding substantially with the bottom of the trough. Extending from the outer sides of the runs of the conveyer 42 are the pairs of teeth 43 which on 30 the upper run of the conveyer extend into the trough so as to carry along bundles of grain which are dropped into the latter. The shaft 44 which carries the sprocket 41 35 extends along the frame-work of the machine through a housing 45, whose forward end terminates above the rear axle of the machine in a yoke 46. Within the yoke 46 a bevel gear 47 carried by the end of the shaft 40 44 meshes with a second bevel gear 48 upon a counter-shaft 49 which is also mounted in the yoke 46. A pinion 50 on the lower end of the shaft 49 meshes with a bevel gear 51 which is mounted upon the rear axle 52 so as 45 to be operated when the machine is drawn over the ground. Engaged with shaft 44 at opposite sides of the trough 40 are the arms A of a yoke B, one arm thereof being formed into a bearing block 53, the shaft 44 being 50 also extended outside of the trough 40 to have its extremity journaled in an extension 54 of the bearing block 53. The bearing block 53 is suspended from the shaft 44, and at its lower end terminates in an annular 55 flange 55 which opposes and coincides with a flange 56 formed on a second bearing block 57, the blocks 53 and 57 being connected by means of a coupling collar 58 which surrounds the flanges 55 and 56. Operative in 60 the blocks 53 and 57, is a vertical shaft 59 whose end is provided with a bevel gear 60 meshing with a second bevel gear 61 keyed upon the end of the shaft 44. The bearing block 57 is extended at one side in a yoke 65 62, and furthermore has in its lower portion

a gear cavity 63. Extending through the cavity 63 and the yoke 62 is a counter-shaft 64 which is geared to the shaft 59 by means of the intermeshing bevel gears 65 and 66 which are keyed, respectively, to the vertical and counter-shafts. Within the yoke 62 70 the counter-shaft 64 supports a sprocket wheel 67, the latter being spaced from the sides of the yoke 62 so as to provide bearings therein for the ears 68 which project inwardly from the vertical flanges 69 of a second trough 70. The trough 70 also carries a conveyer chain 71 which passes over the sprocket 67 at the inner or lower end of the trough and a sprocket 72 at the upper or free end of the trough 70. This chain is also provided with teeth 73, so that bundles which are delivered from the free end of the trough 40 and drop into the lower end of the trough 70 will be carried upwardly in the 80 latter for delivery from its outer end.

The lower end of the bearing block 57 terminates in a standard or pillow 74 whose lower end is supported in a bearing 75 and from which an inclined arm 76 extends. 90 The free end of the arm 76 is bored and threaded to receive one end of an adjusting turnbuckle rod 77, whose other end is oppositely threaded into a second arm 78 which is yoked as at 79 and pivotally connected to the free end of the trough 70. Thus, by manipulation of a cross arm 80 mounted at the middle point of the bar 77, the slant of the trough 70 may be changed. Inasmuch as the bearing block 57 is swiveled to the block 100 53 by reason of its connection with the block 53 through the coupling collar 58, and the lower end of the pillow 74 is rotatable in the bearing 75, the end of the trough 70 may be horizontally directed at will to load bundles 105 into various parts of a vehicle driven alongside this machine. The bearing 75 is formed upon the free end of a rearwardly projecting arm 81, which is furthermore supported by means of a brace rod 82 extending downwardly from the rear portion of the frame-work of the machine.

The machine may be tractor drawn or horse propelled, and is obviously driven so 115 that the rake teeth 12 will gather up bundles or shocks from the field, the elevation of the teeth 12 being primarily adjusted by means of the hand lever 17. With the propulsion of the machine, the conveyers are operated from the rear axle by means of 120 the sprocket gearing above described, the lower run of the upper conveyer and the upper run of the lower conveyer passing upwardly so that grain which is received upon the teeth 12 will be engaged by the 125 conveyers and carried to the upper end of the frames 1 and 2. It should be noted that the upper frame extends for a considerable distance over the teeth 12 so that the lower end of the upper conveyer will operate in 130

a position to engage bundles of grain directly from the teeth, without the necessity of the bundles becoming piled up at the upper end of the rake before they will be engaged by the conveyer. The conveyer chains in the troughs 40 and 70 are operated in an obvious manner, to receive the bundles and deliver them at the outer end of the trough 70, and the manner of adjustment 10 of the latter having been clearly brought out in the foregoing description, it will be obvious that it is possible, by means of this machine to deliver bundles of grain or shocks of grain into suitable transportation vehicles with a minimum of effort, and that 15 a large quantity of grain may be gathered in a comparatively short period of time.

What we claim as our invention is:—

1. In a grain shock loader, a wheeled frame having elevating conveyer means, a trough mounted transversely of the frame at its rear end below the elevating conveyer means and having a central longitudinal opening in its bottom, an endless conveyer movable through the center opening in the bottom of the trough, a vertically and horizontally swinging trough supported at one end of the first named trough and having a central longitudinal opening in its bottom, an endless conveyer movable in the opening of the last named trough, means for vertically adjusting said last named trough, and connections between the conveyers in the troughs for simultaneously operating 35 the same.

2. In a grain shock loader, a wheeled frame having elevating conveyer means, a trough mounted transversely of the frame at its rear end below the elevating conveyer means and having a central longitudinal opening in its bottom, an endless conveyer movable through the center opening in the bottom of the trough, a vertically and horizontally swinging trough sup-

ported at one end of the first named trough 45 and having a central longitudinal opening in its bottom, an endless conveyer movable in the opening of the last named trough, means for vertically adjusting said last named trough, connections between the conveyers in the troughs for simultaneously operating the same, and connections between one of the wheels of the frame and the elevating conveyer mechanism and also the conveyer mechanism in the first named 50 trough for the automatic driving thereof.

3. In a grain shock loader, a wheeled frame having elevating conveyer means, a trough mounted transversely of the frame at its rear end below the elevating conveyer 60 means and having a central longitudinal opening in its bottom, an endless conveyer movable through the center opening in the bottom of the trough, a vertically and horizontally swinging trough supported at one 65 end of the first named trough and having a central longitudinal opening in its bottom, an endless conveyer movable in the opening of the last named trough, means for vertically adjusting said last named trough, 70 connections between the conveyers in the troughs for simultaneously operating the same, connections between one of the wheels of the frame and the elevating conveyer mechanism and also the conveyer mechanism in the first named trough for the automatic driving thereof, and means for supporting the last named trough relative to the first named trough for swinging movement without disturbing the driven connections between the conveyers in said troughs. 75

In testimony whereof we affix our signatures in the presence of two witnesses.
